(57) **CLAIM**

The ornamental design for a beach stake, as shown and described.

DESCRIPTION

FIG. 1 is a front perspective view of a beach stake showing our new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines are for environmental purposes only; the broken lines form no part of the claimed design. The rear of the article (not shown within the drawing figures) forms no part of the claimed design.
